Primary Examiner — Jae Liang*Assistant Examiner* — Anthony Vincent Rotolo(74) *Attorney, Agent, or Firm* — Best & Flanagan LLP(57) **CLAIM**

The ornamental design for a vehicle light, as shown and described.

DESCRIPTION

FIG. 1 is a perspective view of a vehicle light, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged view thereof according to a broken circle “8” shown in FIG. 1 by dash-dot-dot broken lines; the dash-dot-dot broken lines form no part of the claimed design.

The dash-dash broken lines in the drawings illustrate portions of the article that form no part of the claimed design.

1 Claim, 8 Drawing Sheets(56)
